ATTORNEY

UNITED STATES PATENT OFFICE.

PETER KIMACK, OF ST. LOUIS, MISSOURI.

SWITCH-STAND.

1,318,767.

Specification of Letters Patent. Patented Oct. 14, 1919.

Application filed December 7, 1918. Serial No. 265,744.

To all whom it may concern:

Be it known that I, PETER KIMACK, a citizen of the United States, and resident of St. Louis and State of Missouri, have invented certain new and useful Improvements in Switch-Stands, of which the following is a specification containing a full, clear, and exact description, reference being had to accompanying drawings, forming a part thereof.

My invention relates to improvements in switch stands, in which the mechanism connected to the switch points is resiliently connected. A further object is to provide a means whereby the switch point operating mechanism and the lever for operating said mechanism are simultaneously and automatically held in locked position. A further object is to provide a switch stand constructed so that, when the switch is thrown to direct a car from one track to another and when a car passes over the switch in an opposite direction, the shock imparted to the switch points is absorbed by my resilient mechanism, thus obviating the bending of switch points or breaking of the switch stand or any of its component parts.

In the drawings:

Figure 1 is a plan view of my device with parts broken away.

Fig. 2 is a top plan view of my device showing same in neutral or half-thrown position and parts removed therefrom.

Fig. 3 is a longitudinal sectional view of my device taken on the line 3-3 of Fig. 2.

Fig. 4 is a cross-sectional view taken on the line 4-4 of Fig. 2.

Fig. 5 is a view of the locking means with parts in section.

Fig. 6 is a perspective view of one of the spring retaining plates employed.

In the construction of my device, I provide a base 7, which is provided with ears 8. These ears are provided with openings 9 through which the spikes 10 are driven to secure the same to a railroad tie or ties.

The base 7 is provided with upwardly

projecting walls 11 thus forming an open compartment or housing 12. The walls 11 are provided on one side with a half bearing 13 and opposite the bearing 13 is formed a laterally projecting housing 14, the bearing 13 and the lateral housing 14 being provided with ears 15, which ears are perforated as indicated by the numeral 16, so that the cover 17 may be securely attached thereto. The cover 17 consists of a flat plate 18 having a semi-circular projection 19 mid-way its length and depending flanges 20 approximately surrounding the cover.

Within the housing 12, I place a secondary housing 21, which is composed of channel bars 22 and ends 23, thus forming a slot 24 through which the arm 25 projects. Within the housing 21 is located a casting 26, this casting being provided with a central slot 27, which receives the forked end 28 of the arm 25. Between this fork and within the casting is located a roller 29, which is mounted on a short shaft 30, the object of the roller being to eliminate as much friction as possible.

Each end of the casting 26 is provided with a projecting lug 31 over which a spring retaining hook 32 is secured. Between the ends 33 of the hooks 32 and the ends of the casting 26, I interpose coiled springs 34, these coiled springs serving as a shock absorber when wheels are passing in a counter switch direction or, in other words, it will allow the flanges of the wheels, when approaching from a direction opposed to the switch points, to spread or force the switch points away from the track, thus obviating the bending of the switch points or the breaking of the switch stand. These springs are secured in a slightly compressed state, thus holding the hooks 32 rigid and secure at all times.

On top of the housing 21 is secured a rack 35, which meshes with a pinion 36. The pinion 36 is securely fastened to a shaft 37. This shaft operates in the bearing 13 formed in the housing. The end of the

shaft 37, which projects through the housing, is provided with a square socket 38 into which the switch throwing lever 39 is secured. This switch throwing lever is preferably square and is provided at its outermost end with a weight 40.

The end of the arm 25, opposite the fork, is provided with a boss 41, this boss 41 being provided with a square hole 42 through 10 which the target stand 43 projects. This target stand extends entirely through the boss 41, through a second boss 44 and into a lever 45. This lever is in turn secured to a rod or switch bar 46 which is connected 15 with one of the switch points 47 and from this switch point 47, another bar 48 extends to the opposite switch point, thus causing both points to operate simultaneously.

The housing 11 is further provided with a 20 pair of projections 49 in which spring actuated locking hooks 50 are located. Each of these spring actuated locking hooks is provided with an upwardly extending hook member 51 and a foot treadle 52. The pin 25 53 is secured to the upwardly extending locking member of the hook and operates simultaneously therewith. In other words, when the treadle 52 is depressed, the member 51 releases the switch throwing bar 39 30 and at the same time withdraws the pin 53. The pin 53 serves as an additional locking device, in that it secures the housing 21 from shifting, this being clearly shown in Fig. 1.

It is to be understood that my device may 35 either be secured to two ties, as shown in the drawings, or the same may be placed sidewise and secured to only one tie and still be operative. Furthermore, I may extend the arm 45 on the opposite side of the 40 laterally projecting housing and work a second switch simultaneously with the first switch without departing from the spirit of my invention.

I may, if desired, provide the projections 45 49 with perforated ears 54, through which a locking device can be inserted and a switch stand securely locked, so that it cannot be tampered with, this being expressly desirable when my stand is used for siding, or 50 switches which are removed from railroad yards.

It will also be further observed that, when the switch operating lever 39 is locked as 55 illustrated in Fig. 1, the pin 53 rests against one end of the movable or secondary housing 21 and the opposite end of said housing rests against the inside end of the housing 12, thus securely holding the inner housing 21, as it were, in locked position and when 60 the switch operating lever 39 is reversed, the operation is repeated in so far as locking the secondary housing is concerned; it being noted, that the housing 21 is never locked unless the lever 39 is in locked position.

Having fully described my invention, what I claim is:

1. A switch stand comprising a switch operating bar, an operating means resiliently connected to said switch operating 70 bar, and a lever mechanism connected to said resilient means for placing the switch operating bar in operation.

2. A switch stand comprising a switch operating bar, an operating means resiliently connected to said switch operating 75 bar, a lever mechanism connected to said resilient means for placing the switch operating bar in operation, and a means for locking the resilient means in position when 80 the switch is thrown.

3. A switch stand comprising a housing, a lever mechanism located partially within said housing, a second lever mechanism located partially within said housing and resiliently connected to the first mentioned 85 lever mechanism in combination with a pair of switch points to which said second mentioned lever mechanism is attached.

4. A switch stand comprising a housing, 90 a second housing mounted within the first mentioned housing, said second mentioned housing being provided with a lateral slot, a rack carried by said second mentioned housing, a bifurcated lever pivotally mounted in the first mentioned housing and extending through the lateral slot formed in the second mentioned housing, a shock absorbing spring mounted on each side of the bifurcated lever and within the second mentioned housing, a bar for operating the 95 points of a switch and a lever mechanism mounted in the first mentioned housing for shifting the second mentioned housing from side to side.

5. A switch stand comprising a housing, a second housing mounted within the first mentioned housing, said second mentioned housing being provided with a lateral slot, a rack carried by said second mentioned 110 housing, a bifurcated lever pivotally mounted in the first mentioned housing and extending through the lateral slot formed in the second mentioned housing, a shock absorbing spring mounted on each side of the bifurcated lever and within the second mentioned housing, a bar for operating the 115 points of a switch, a lever mechanism mounted in the first mentioned housing for shifting the second mentioned housing from side to side, and a means for preventing the second mentioned housing from shifting when the lever is thrown.

6. A switch stand comprising a switch point operating bar, a switch throwing 125 lever, a resilient lever connection between said switch bar and switch throwing lever, and means for simultaneously locking the switch throwing lever and the resilient lever connection.

7. A switch stand comprising a switch point operating bar, a switch throwing lever, a stationary housing located between the same, a movable housing mounted in the stationary housing, a lever for operating the switch operating bar, and a resilient connection between the movable housing and the switch point operating bar.

In testimony whereof, I have signed my name to this specification, in the presence of 10 two subscribing witnesses.

PETER KIMACK.
